(57) **CLAIM**

The ornamental design for a passenger grab handle as shown and described.

DESCRIPTION

FIG. 1 is a left perspective view of a passenger grab handle showing my new design;

FIG. 2 is a right side elevational view thereof, the left side elevational view being a mirror image;

FIG. 3 is a front elevational view thereof;

FIG. 4 is a rear elevational view thereof;

FIG. 5 is a top plan view thereof; and,

FIG. 6 bottom plan view thereof.

The broken lines illustrate and surround portions of the passenger grab handle which form no part of the claimed design.
